HINGE DEVICES FOR PIVOT TYPE WINDOWS

Gustaf Per Henry Lundgren, Stockholm, Sweden

Application February 1, 1951, Serial No. 208,864

8 Claims. (Cl. 16—140)

The present invention relates to pivot type windows, i. e. to such windows in which hinge devices are positioned substantially on the horizontal, or in some cases the vertical, centre line of the window. More particularly the invention relates to hinge devices for pivot type windows.

In pivot type windows having the hinge devices arranged substantially on the horizontal centre line of the window the hinge devices usually are mounted so that the axis, about which the window pivots when moving from closed position to full ventilating position, takes up such a position with respect to the centre of gravity of the movable window as to secure the desired degree of balancing of the window. It is thus possible, for instance, to let the pivot axis of the hinge devices pass through the centre of gravity, resulting in a complete balancing of the window, or else it can be arranged that the turning axis is displaced a certain distance from the centre of gravity in such a direction, that the window tends to turn or swing itself either from its closed position to its fully open position, or, alternatively, from its fully open position to its closed position, for example. Irrespective of the positioning of the turning axis of the window it is customary to provide the hinge devices with a brake, which opposes the turning of the window and holds the window in the position to which it has been turned.

As long as it can be assumed, that the window has a definite centre of gravity, the requirements on the brake can be held low by placing the hinge devices so that a sufficient degree of balancing of the window about the turning axis is obtained. Lately it has, however, become customary to provide a Venetian blind between the panes of the window, and as a result the position of the centre of gravity relatively to the turning axis will depend on whether the Venetian blind is fully hoisted or fully or partly lowered. If the window is suitably balanced when the Venetian blind is wholly lowered, the window will evidently be top-heavy when the Venetian blind is fully hoisted, and it will then be difficult for the brake to hold the window in intermediate positions in which it is set. Therefore, there is now a demand for more effective hinge brakes for pivot type windows.

The present invention has for its object to meet said demand by improving the brake device in hinge devices for pivot windows, particularly windows adapted to pivot on a horizontal axis.

According to this invention in a hinge device for hinged windows a first part of the hinge device is provided with a circularly or otherwise curved channel housing a braking member, the said braking member being movable along the channel by a driving member on a second part of the hinge device upon movement of the window, and the braking member is expansible by means of a set screw and adapted to press with an adjustable pressure against the opposing parallel curved surfaces of the channel.

Two embodiments of the invention will now be described, by way of example, with reference to the accompanying drawings wherein:

Figure 1 shows a hinge device comprising one embodiment of the invention, as viewed from the outside of a window,

Figures 2, 3 and 4 show the same vertical section taken on the line 2—2 in Figure 1 but with the hinge parts shown in different relative turning positions,

2

Figure 5 shows another hinge device comprising the second embodiment of the invention, as viewed from the outside of a window, and

Figures 6, 7 and 8 show the same vertical section taken on the line 6—6 in Figure 5 but with the hinge parts shown in different relative turning positions.

In Figures 1 to 4 of the drawings the part of the hinge device which is adapted to be secured to the window frame consists of a plate 11 provided with holes 10 for fixing screws, to which plate there are secured, for example by welding, two parallel circularly bent flanges 12 and 13 having a common axis 14 perpendicular to the plate 11. The flanges 12 and 13 define between themselves a guide channel 15 of uniform width in which ride two pins 16 and 17 mounted on a plate 18, which is adapted to be secured by means of screws to the window sash, the said plate 18 preferably having the same shape as the plate 11. A brake member 19 is inserted in the guide channel 15 between the pins 16 and 17. The said brake member 19 consists of a band of spring steel which is bent approximately to the shape of a U, the branches 20 and 21 of the U-shaped spring bearing against the guide flanges 12 and 13 respectively and the free ends of the two branches being bent over inwardly towards each other so that overlapping lugs 22 and 23 respectively are formed, the overlapping lugs extending transversely of the guide channel 15.

A slit 24 is provided in the guide flange 13 with the longitudinal axis of the slit extending parallel to the plane 30 of the plate 11. The slit is of sufficient width to receive a screw 25 which is screwed into a threaded hole at about the middle of the inner branch 21 of the spring 19. The screw 25, which is provided with a round head having a central hexagonal hole for a screw driver, is intended to be screwed in sufficiently far for its free end to engage the opposite branch 20 of the brake spring 19 with a suitable pressure. As the pressure of the screw 25 on the branch 20 increases the force with which the spring 19 presses against the walls 12 and 13 of the guide channel will also be increased and thus also the braking action of the spring. Besides regulating the braking action of the spring the screw 25 co-operates with the slit 24 and serves to limit the path along which the braking spring 19 can move in the guide slot 15.

The hinge device just described operates in the following manner.

When the window is closed the two main parts of each hinge device, one device being provided at each side of the window, take up the relative positions shown in Figure 5. During turning of the window to its ventilating position, the pins 16 and 17 move along the guide slot 15, the window turning about a fixed horizontal axis coincident with the axis 14. The pins 16 and 17 move the spring 19 in the guide slot 15 and, due to the engagement of the spring 19 with the guide flanges 12 and 13, the turning movement is braked thereby. By suitable regulation of the spring force, by means of the screw 25, the braking effect can be made sufficiently great for the window to be securely held by the braking spring 19 in every desired position in which it is set. The turning of the window about the horizontal axis coincident with the axis 14 is continued until the setting screw 25 engages the lower end of the slit 24. This last-mentioned position of the window corresponds to the normal fully-open position. If the upper edge of the window is now moved further in the same direction, the window will pivot about the trailing pins 16 resting in fixed bearings, each of which is formed by the outermost lug 23 on the arrested braking spring 19 and the associated guide flanges 12 and 13. Meanwhile the leading pin 17 is swung free from the guide channel 15, as is shown in Figure 4. If the hinge devices are suitably placed it is possible to turn the window

through 180 degrees so that the outside of the window becomes readily accessible for cleaning.

In the embodiment shown in Figures 5 to 8 the braking member consists of two substantially rigid brake shoes 120 and 121, which are adapted to be pressed apart by a set screw 122 into engagement with the brake paths formed by walls 112 and a guide flange 113 of the guide channel 15. The set screw 122 is screwed into a threaded bore in the inner brake shoe 121 and has its smooth free end inserted into a corresponding shallow recess 123 in the outer brake shoe 120.

The set screw 122 is provided with a round head having a central hexagonal cavity for a screw driver and is accessible for adjustment through a slit 124 in the guide flange 113. The slit 124 is of uniform width and has its longitudinal axis parallel to the plate 11.

When the set screw 122 is screwed towards the guide flange 112 the flanges 112 and 113 are resiliently pressed somewhat apart, wherefore, in spite of their rigidity, the brake shoes 120 and 121 are pressed against the brake paths with resilient pressure and the braking action increased. If desired, the brake shoes can be made elastically compressible to a certain degree, for example by providing the braking surfaces of the shoes with some elastically-compressible lining material.

In this embodiment the set screw 122 protrudes through the slit 124 and in addition to regulating the braking action co-operates with the ends of the slit 124, to determine the extent of the path along which the brake shoes 120 and 121 are movable in the slot 15.

When the window is closed the two main parts of each hinge device, one of which is provided on each side of the window, take up the relative positions shown in Figure 6. During turning of the window to its ventilation position the pins 16 and 17 move along the guide slot 15, the window turning about a fixed horizontal axis coincident with the axis 14, the pins 16 and 17 move the shoes 120 and 121 which, owing to their engagement with the guide flanges 112 and 113, brake the turning movement. By suitable regulation of the bearing pressure by means of the set screw 122, the braking effect can be made sufficiently great to ensure that the window is securely held by the brake shoes 120, 121 in every position in which it is set. The turning of the window about the horizontal axis coincident with the axis 14 is continued until the set screw 122 engages the lower end of the slit 124. The said position of the window corresponds to its normal fully-open position. If the upper edge of the window is now swung further in the same direction the window will pivot about the pins 16 in fixed bearings each of which is formed by the brake shoes 120, 121, which are now stationary, and by the associated guide flanges 112 and 113, the pins 17 then swinging out from the guide channel 15, as shown in Figure 8. If the hinge devices are suitably placed it is possible to turn the window through 180 degrees so that the outside of the window becomes accessible for cleaning.

I claim:

1. A hinge device for pivot type windows which comprises a first hinge part having a curved guide channel of even width, a second hinge part having two pins guided in said channel, an expandible braking member housed in said guide channel between said pins and adapted to be moved along the channel by coaction with the pins upon relative movement of the two hinge parts, and a set screw for expanding said braking member, said set screw extending transversely to the opposing surfaces of said curved guide channel to cause the braking member to press with an adjustable pressure against both of said surfaces.

2. A hinge device for pivot type windows which comprises a first hinge part having a circularly shaped guide channel of even width, said guide channel comprising a fixed plate having two arcuately bent flanges projecting therefrom, a second hinge part having two pins guided in said channel, an expandible braking member housed in

the guide channel between said pins and adapted to be moved along the channel by coaction with the pins upon relative movement of the two hinge parts, an expanding screw operatively connected with said braking member and extending transversely to the surfaces of said guide channel flanges to cause the braking member to press against said channel surfaces, and a circumferentially extending slit in one of said guide channel flanges, said expanding screw having its free end projecting through said slit for coaction therewith to arrest the movement of the braking member in a position whereby the braking member together with the walls of said guide channel forms a fixed bearing for one of said pins so that upon further movement of the window said hinge device is adapted to pivot about said last mentioned pin.

3. A hinge device as claimed in claim 2 wherein the expandible braking member consists of a band spring which is substantially U-shaped, and the braking member expanding screw is arranged to be screwed through a threaded hole in one branch of said band spring and to press against the inside of the other branch of the spring.

4. A hinge device as claimed in claim 2 wherein the expandible braking member consists of a band spring which is substantially U-shaped, and the braking member expanding screw is arranged to be screwed through a threaded hole in one branch of said band spring and to press against the inside of the other branch of the spring, at least one of the said spring branches being curved so that on being tightened said expanding screw tends to straighten out said spring branch while increasing the pressure of the branches of said U-shaped spring member against the opposing braking surfaces of the guide channel.

5. A hinge device for pivot type windows which comprises a first hinge part having a curved guide channel of even width, a second hinge part having two pins guided in said channel, a pair of rigid braking shoes housed in said guide channel and arranged between said pins, said braking shoes being moved along the channel by said pins upon relative movement of the two hinge parts, a set screw operatively connected with said brake shoes, said set screw extending transversely of the opposed curved surfaces of said guide channel and being adapted to press said brake shoes apart and against both of the curved surfaces of the channel with an adjustable pressure.

6. A hinge device as claimed in claim 5 wherein the walls forming the guide channel consist of two circularly bent flanges projecting from a fixing plate, the flanges being connected together only through the intermediary of said plate whereby the channel formed between the flanges is fully open towards the second hinge part.

7. A hinge device as claimed in claim 5 wherein the said set screw projects through an elongated circumferentially extending opening in one of the walls of said guide channel and is adapted to engage in one end of the said opening when the window mounted by the hinge device has been moved to full ventilating position, the braking shoes being then arrested so as to form together with the walls of said guide channel a fixed bearing for the trailing one of the two pins riding in the channel whereby the window is adapted for pivoting about said trailing pin when the window is opened further.

8. A hinge device as claimed in claim 2 wherein said expandible braking member is adapted to press resiliently against the opposing braking surfaces of the guide channel.
